SAFETY STOP ATTACHMENT FOR FULL-FASHIONED HOSIERY MACHINES

Troy H. Decker, Hildebran, N. C., assignor of one-half to Alexander B. Vinay, Valdese, N. C.

Application April 22, 1949, Serial No. 88,974

10 Claims. (Cl. 66—157)

1

This invention relates to a safety device for a full-fashioned hosiery machine, and more particularly to a switch-actuating device for stopping the machine when the slur cock bar and friction bar are accidentally caused to move separately out of phase.

It is an object of this invention to provide a safety stop attachment of the kind to be more particularly described hereinafter, particularly designed for a full-fashioned hosiery machine of the type represented by the "Karl Lieberknecht Full Fashion Hosiery Machine No. 2096—With Kalio Automatic Welt Turner."

In the narrowing of the main part of the leg of the hosiery being formed by the machine, when the machine narrows, the two coulier cams are stopped by means of a brake and both gears for driving the coulier cams from the main cam shaft are caused to be shifted out of gear from the main cam shaft. These gears stay out of gear while the main cam shaft makes a complete turn, at which time clutch means cause positive engagement with the main cam shaft and the cams continue in normal operation. If either coulier cam gear is not properly re-engaged with the cam shaft, that particular cam will not operate for a complete cycle of operation of the machine, at which time it will operate reversely of the other cam causing much damage to the sinkers, dividers and needles. With the use of a stop device constructed according to the teachings of this invention, when one of the cams comes out of the designed specific timed relation between the cams, the machine is immediately and automatically stopped until properly reset, thus preventing any costly damage of this kind with its resultant loss in time and operation of the machine.

With the above and other objects in view, my invention consists in the arrangement, combination and details of construction disclosed in the drawings and specification, and then more particularly pointed out in the appended claims.

In the drawings:

Figures 1 and 1-a are a continuous rear elevation, partly broken away, of a full-fashioned hosiery machine, having a stop mechanism constructed according to an embodiment of my invention;

Figure 2 is a fragmentary horizontal section, taken on the line 2—2 of Figure 1;

Figure 3 is a fragmentary vertical section, taken on the line 3—3 of Figure 1;

Figure 4 is a fragmentary vertical section, taken on the line 4—4 of Figure 1;

2

Figure 5 is a fragmentary front elevation, partly broken away, of the lever arm shown in Figure 3.

Referring to the drawings, the numeral 10 designates generally a full-fashioned hosiery knitting machine having a separately-driven friction bar 11 and a slur or slur cock bar 12. The knitting machine 10 is formed with a basic frame having end members 14 and longitudinally-extending frame members 15 and 16.

The friction bar 11 is oscillated on the frame of the machine 10 by a coulier mechanism which includes a coulier cam 17 and a rock lever 18 connected at its upper free end to the friction bar. The lower end of the friction-bar-actuating lever 18 is pivotally mounted on the lower frame member 16. The cam 17 is rotatably mounted on a supporting member 19 carried by the frame 16 and is engaged by a cam-following member 20 which is pivotally connected to the friction-bar-actuating lever 18 intermediate the length thereof.

The slur bar 12 is oscillated on the frame by a separate coulier mechanism which includes a slur-bar-actuating lever 21 pivoted at its upper end on the slur bar 12 and at its lower end on a fitting 22 carried by the lower frame member 16. A coulier cam 24 is rotatably mounted on a supporting member 25 also fixed on the frame member 16, the cam 24 being engaged by a cam-following member 26 which is pivotally connected at one end to the slur-bar-actuating lever 21 intermediate the length thereof. The operating means for the friction bar 11 and slur bar 12 are clearly shown in Figure 1a of the drawings.

In this type of full-fashioned hosiery knitting machine, the coulier cams 17 and 24 are adapted to be driven by conventional driving means from a common, main cam shaft. A main cam shaft 40 extends along the length of the machine 10, and when the machine narrows in the narrowing of the main part of the leg of the hosiery to be knitted, the cams 17 and 24 are stopped by means of a brake, and the driving means for both of the 45 cams are shifted out of gear from engagement with the main cam shaft. The main cam shaft and the driving or gear means by which the same are connected to the main shaft are not shown in the drawings, such structure being conventional in this type of machine.

When the machine has completed the narrowed portion of the leg of the hosiery, the driving means for the cams 17 and 24 are re-engaged with the main cam shaft to actuate the cams 17 and 24, and frequently at this time one of the

gear mechanisms will not properly engage the main cam shaft and at such time the cams 17 and 24 will be caused to be actuated in an out-of-phase relation. In the normal operation of the cams 17 and 24, that is, in the in-phase relation, both of the cams 17 and 24 are rotated in the same angular relation to effect the simultaneous reciprocation or oscillation of the slur bar 12 and friction bar 11. During the narrowing of the leg of the hosiery, the driving means for the cams 17 and 24 are in and out of engagement with the main cam shaft about a hundred times. When the driving means for the coulier cams 24 and 17 are engaged with the main drive shaft, in an out-of-phase relationship, the friction bar 11 and slur bar 12 are actuated in opposite directions, and such movement causes the heavy damage to the sinkers, dividers and needles of the machine. The automatic machine-stopping device of this invention is particularly designed for stopping the machine when the driving means for the cams 17 and 24 are not engaged with the main drive shaft in the proper timed relation for effecting the simultaneous oscillation of the friction bar and slur bar.

The main cam shaft, not shown in the drawings, is operated by an electric motor, which, in turn, is controlled by a main control switch 27 placed on the lower frame member 16. The switch 27 is formed with a contact-controlling plunger 28 reciprocable therein for opening and closing the circuit to the electrical power means for the knitting machine. In the normal position of the plunger 28, the extended position, the contacts within the switch 27 are closed, whereas, with the plunger 28 within the switch 27, the contacts are open for breaking the circuit to the driving means for the knitting machine 10.

Switch actuating means are provided comprising a pair of brackets or hangers 29 and 30 which are fixed to the upper frame member 15 on the lower side thereof and extended downwardly therefrom. A bearing 31 is fixed to or formed on the forwardly-extending arms 32 of the hangers 29 and 30 and an elongated pivot member or pivot bar 34 is journaled in the bearings 31. The pivot member 34 extends along the length of the machine 10 parallel to the parallel bars 11 and 12 and is of a length substantially equal to the length of travel of the bars 11 and 12 effected by the normal operation thereof. A depending lever arm 35 is fixed to the pivot bar 34 intermediate the length thereof between the hangers 29 and 30 and is adapted to engage the switch button or arm 28 for breaking the circuit to the electric motor, not shown in the drawings, which drives the main cam shaft. A spring lever arm 36 is fixed on the pivot member 34 adjacent one end thereof and extends upwardly therefrom. A spring 37 is engaged between the extreme upper end of the spring lever arm 36 and a fixed part of the frame or bracket from which the hanger 30 depends for constantly biasing the switch-lever arm 35 out of engagement with the switch-actuating plunger 28. In the normal position of the knitting machine 10, the depending switch-actuating lever arm 35 is in the position shown in Figure 4 of the drawings, the lower end of the lever arm 35 being in its outermost position in relation to the switch 27, so that the plunger 28 is fully extended from the switch and the contacts within the switch are closed for completing the electrical circuit. In this form of the invention, the lever-supporting brackets 29 and 30 are engaged over the jack spring bearings, the

hangers 29 and 30 replacing the plate which normally closes the jack spring bearings 38.

A pair of lever arms 39 and 40 are fixed on the pivot bar 34 adjacent the opposite ends thereof and extend upwardly therefrom. The lever arms 39 and 40 are spaced apart a distance slightly greater than the maximum length of travel of the friction and slur bars 11 and 12. A horizontal lever bar 41 is fixed between the upper ends of the lever arms 39 and 40, the lever bar 41 being positioned parallel to the length of the friction bar and slur bar, and parallel to the pivot bar 34.

Means adapted to be actuated by out-of-phase movement of the bars 11 and 12 are connected to one of said bars and are illustrated as being secured to the friction bar 11 and comprising a pivot or lever supporting bracket 42 which is secured along the length of the friction bar 11 and extends forwardly from one side thereof. The lever-supporting bracket 42 is substantially L-shaped in configuration, being inverted, having a substantially horizontally-extending arm 44 which is adapted to be engaged on the friction bar by set screws 45, or other suitable fastening devices. The bracket 42 is further formed with a depending, recessed, vertically-extending arm 46 within which an L-shaped lever or rack arm 47 is pivotally engaged. The lever 47 is pivoted at the upper end of its vertically-extending arm 48 by a pivot pin 49 which is extended across between the side arms of the vertically-extending, recessed arm 46 of the bracket 42. A set screw 43 is threadably engaged through the rear side of the vertically-extending arm 46 of the bracket 42 and is adapted to engage the inner side of the lever 47 for limiting the inward swinging movement of the lever. The lower, inwardly-extending arm 50 of the lever 47 extends inwardly for engagement with the slur bar 12. In the normal position of the cams 17 and 24, with the friction bar 11 and slur bar 12 operating in the desired manner, the lever 47 will lie close within the recess of arm 46 of the bracket 42 and a spring-pressed pin 51 will abut one side edge of the vertical arm 48 of the lever 47. The spring pin 51 is carried by a spring 52 which is fixed on one side of the vertical arm 46 of the bracket 42. Upon swinging movement of the lever 47 outwardly in relation to the bracket 42, the pin 51 will be spring-pressed inwardly within the recess of vertical arm 46 for holding the vertical arm 48 of the lever 47 against returning to its normal position before the friction bar 11 and slur bar 12 are properly positioned for normal operation.

A pair of lever actuating or lift members such as cam members or cams 54 and 55 are secured along the length of the slur bar 12 for engagement with the inwardly-extending arm 50 of the lever 47. The cam members 54 and 55 are substantially U-shaped in configuration, and adapted to be engaged about the forward edge of the slur bar 12. The cam members 54 and 55 are slightly spaced apart along the length of the slur bar 12 and are formed with outwardly-inclined faces 56 and 51, respectively, confronting each other on the opposite sides of the spaced-apart opening between them. The cam members 54 and 55 are positioned in such a manner that when the bars 11 and 12 are moving in an out-of-phase relation, the inwardly-extending arm 50 of the lever 47 will be caused to be lifted by the cams 54 and 55 for breaking the circuit to the driving means for the knitting machine. The extreme inner end of the horizontally-extending arm 50

of the lever 47 is formed with outwardly-inclined faces 58 and 59 which are adapted to slidably engage on the confronting cam lift faces 56 and 57 of the cam members 54 and 55, respectively. In the normal position of the lever 47 in relation to the cams 54 and 55, the inwardly-extending arm 50 will be positioned between the cams 54 and 55, being spaced apart from each of them. The normal operation of the bars 11 and 12 will maintain this relative position between the lever 47 and the cams 54 and 55, the normal operating position being clearly shown in Figure 2 of the drawings.

A depending pin or lug 60 is fixed on the lower side of the inwardly-extending arm 50 of the lever 47 and is adapted to engage the inner edge of the longitudinally-extending lever bar 41. In the normal operation of the knitting machine 10, the pin 60 will slide along the length of the lever bar 41, the sliding of the pin 60 being effected by the reciprocating motion of the friction bar 11 and slur bar 12.

In the normal operation of the knitting machine 10 the lever 47 will be positioned between the cam members 54 and 55, and the pin 60 will slide along the length of the lever bar 41 on the inner side thereof. When the machine is operating out of phase or starts to operate out of phase, the friction bar 11 and slur bar 12 will not be moving simultaneously and therefore the difference in the movement between the bars will effect the positioning of the cam members 54 and 55 in relation to the inwardly-extending arm 50 of the lever 47. This disposition of the arm 50 in relation to the cams will effect the lifting or moving forwardly of the lower arm 50 of the lever 47 and the rocking of the lever about its pivot pin 49. As the lever 47 moves outwardly, the pin 60 will engage the inner surface of the longitudinally-extending lever bar 41 for pivoting the lever arms 39 and 40 about the pivot bar 34. As the lever arms 39 and 40 are moved outwardly, the lever arm 35 will be moved inwardly and press the plunger 28 of the switch 27 within the switch for breaking the electrical circuit to the main driving means. At this time, the brakes on the electric motor which drives the cam members 17 and 24, not shown in the drawings, will effect the immediate stoppage of the machine until such time as the proper relationship between the friction bar 11 and slur bar 12 can be reset. As the lever 47 is moved outwardly to stop the machine, the pin 51 will be pressed inwardly to hold the lever from returning to its normal position and inadvertently starting the machine. For restarting the machine, the pin 51 must be pulled outwardly against the tension of the spring 52 for positioning the lever 47 in its normal position between the cam members or lift members 54 and 55.

I do not mean to confine myself to the exact details of construction herein disclosed, but claim all variations falling within the purview of the appended claims.

I claim:

1. In a full-fashioned knitting machine having a fixed frame, a pair of parallel, reciprocating bars, independent, in-phase driving means for actuating said reciprocating bars, a main switch for said driving means, a switch-actuating member pivoted on said frame normally urged to switch-closing position, a pair of spaced-apart cam elements on one of said bars, means engageable by said cam elements carried by the other bar and normally disposed between said

cam elements for displacement by said cam elements upon out-of-phase movement of said parallel bars and said means being engageable with said switch-actuating member for opening said switch when the bars and driving means become out of phase.

5 2. In a full-fashioned knitting machine having a fixed frame, a pair of parallel, reciprocating bars, independent, in-phase driving means for actuating said reciprocating bars, a main switch for said driving means, switch-actuating means pivoted on said frame including an elongated lever bar parallel to said reciprocating bars and extending along the length of travel thereof, and cooperating members carried by said reciprocating bars operable when the reciprocating bars become out of phase for actuating said switch to driving-means-stopping position.

10 3. In a full-fashioned knitting machine having a fixed frame, a pair of parallel, reciprocating bars, independent, in-phase driving means for actuating said reciprocating bars, and a main switch for said driving means, switch-actuating means pivoted on said frame including an elongated lever bar parallel to said reciprocating bars and extending along the length of travel thereof, and cooperating members carried by said reciprocating bars operable when the reciprocating bars become out of phase for actuating said switch to switch-opening position.

15 4. In a full-fashioned knitting machine having a fixed frame, a pair of parallel, reciprocating bars, independent, in-phase driving means for actuating said reciprocating bars, a main switch for said driving means, cooperating switch-actuating levers carried by said frame and one of said bars, and a lever-actuating member carried by the other bar engageable with one of said switch-actuating levers for actuating said switch to machine-stopping position when said bars become out of phase.

20 5. In a full-fashioned knitting machine having a fixed frame, a pair of parallel, reciprocating bars, independent, in-phase driving means for actuating said reciprocating bars, a main switch for said driving means, cooperating switch-actuating members carried by said frame and one of said bars, and an actuating member carried by the other bar engageable with one of said switch-actuating members for actuating said switch to machine-stopping position when said bars become out of phase.

25 6. A full-fashioned knitting machine having a fixed frame, a pair of parallel, reciprocating bars, in-phase driving means for said reciprocating bars, a main switch for said driving means, and cooperating switch-actuating elements carried by said frame and said bars for actuating said switch to machine-stopping position when said bars become out of phase.

30 7. Automatic safety stop mechanism for a straight electric motor driven knitting machine having two parallel members and separate means for reciprocating the members endwise in synchronization during knitting, said mechanism including a switch in circuit with the motor, switch actuating means and means carried by one of the reciprocating members for operating the actuating means to actuate the switch and thereby 35 open the circuit in the event of differential movement between the members.

35 8. In a full-fashioned knitting machine having a fixed frame, the combination of a friction bar reciprocably mounted on said frame, a slur bar reciprocably mounted on said frame in

spaced parallel relation to said friction bar, means for reciprocating said friction bar and said slur bar in simultaneous in-phase relation to each other including a pair of cam shaft driven coulier cams, switch means for the machine, an elongated pivot member pivotally mounted on said fixed frame in spaced parallel relation to said friction bar and said slur bar, a lever arm fixedly secured at one end to said pivot member said switch means being engageable by the free end of said lever arm, said pivot member also having an elongated lever bar fixedly secured in spaced relation thereto and along the length of travel of said friction bar and said slur bar, a rock arm pivotally secured at one end to said friction bar and extending past said slur bar, said elongated lever bar being engageable by the free end of said rock arm, lift members on said slur bar engageable with said rock arm upon out-of-phase movement of said friction bar and said slur bar to actuate said elongated lever bar, said pivot member and said lever arm to move said switch means to switch-open position for stopping said machine.

9. In a full-fashioned knitting machine having a fixed frame, the combination of a pair of reciprocating bars reciprocably mounted on said frame in spaced parallel relation to each other, means for reciprocating said reciprocating bars in simultaneous in-phase relation to each other including a pair of cam shaft driven coulier cams, switch means for the machine, an elongated pivot member pivotally mounted on said fixed frame in spaced parallel relation to said reciprocating bars, said pivot member having a lever arm

30
5
10
15

fixedly secured at one end thereto, said switch means being engageable by the free end of said lever arm, said pivot member also having an elongated lever bar fixedly secured in spaced relation thereto and extending along the length of travel of said reciprocating bars, said elongated lever bar being engageable by the free end of said rock arm, lift members mounted on the last-named reciprocating bar and engageable with said rock arm upon out-of-phase movement of said reciprocating bars to actuate said elongated lever bar, said pivot member and said lever arm to move said switch means to machine-stopping position.

10. An electric motor driven, full fashioned knitting machine having a fixed frame, a pair of parallel reciprocating bars, means for reciprocating said bars endwise in timed relation, a switch for the motor and cooperating switch actuating elements carried by said frame and said bars for actuating said switch to machine stopping position when said bars become out of time.
